BUMPER AIR SCOOP

Jack M. Hamond, 6530 Camden Ave.,
San Jose, Calif. 95120

Filed Sept. 4, 1970, Ser. No. 24,854

Term of patent 14 years

Int. Cl. D12—16

U.S. Cl. D14—6

FIG. 1 is a perspective view of the bumper air scoop embodying my new design as applied to a vehicle;

FIG. 2 is a front elevation view of the bumper air scoop as applied to a vehicle;

FIG. 3 is a top plan view of the bumper air scoop; and

FIG. 4 is a side view of the bumper air scoop.

The elements shown in broken lines are included for illustration purposes only.

I claim:

The ornamental design for a bumper air scoop, as shown and described.
